BOW FACING OARLOCK

Elwin R. Kosey, Ontonagon, Mich.

Application September 2, 1943, Serial No. 500,973

1 Claim. (Cl. 9—25)

1

This invention relates to an oarlock construction and aims to provide an efficient oar which is operable facing the front of the boat in order to enable the oarsman to readily view the scenery, which is a distinct advantage in rivers having swift currents, whirlpools and rapids, and which also adds to the pleasure of fishing.

In addition to increasing the safety of rowing, the construction provides a minimum of moving parts and is relatively simple and inexpensive to manufacture.

The more specific objects and advantages will become apparent from a consideration of the description following taken in connection with accompanying drawings illustrating an operative embodiment.

In said drawings:

Figure 1 is a plan view showing the boat fragmentarily, equipped with a set of the improved oarlocks;

Figure 2 is a vertical section taken on the plane of line 2—2 of Figure 1;

Figure 3 is a horizontal section, on an enlarged scale, taken through portions of the oarlock and looking downwardly onto the boat;

Figure 4 is an enlarged section taken on the line 4—4 of Figure 1;

Figure 5 is an enlarged section taken on the line 5—5 of Figure 4, and

Figure 6 is an enlarged section taken on the line 6—6 of Figure 1.

Referring specifically to the drawings wherein like reference characters designate like or similar parts, a boat conventionally and fragmentarily shown at 10 is equipped with a set of my improved oar locks, the latter being generally designated 11 and shown one at each of the opposite sides of the boat and arranged so that the operator or oarsman will face the bow of the boat to add to the safety, efficiency and a pleasure of rowing.

Each structure 11 utilizes any suitable clamp at 12, for instance one of inverted U-shape as shown which straddles the upper edge portion of the sides of the boat and are fastened thereto detachably by bolts as at 13. Pivoted to the clamps or brackets 12 are elongated plates 14. Such plates have integral depending barrels 15 which interfit between barrels 16 on the brackets 12 and through which barrels 15 and 16, pintles 17 are passed, the latter being preferably in the form of bolts as shown. Thus the plates 14 are mounted to swing on horizontal axes disposed longitudinally of the boat.

The oars each comprise blade and operating

2

sections 18 and 19, respectively. Said sections respectively, preferably have metallic sockets at 20 and 21, and the former has an extension 22 fitted between and pivoted to ears 23 of the section 21 through which detachable bolts 24 pass to pivotally secure the oar sections together. Sockets 20 are also pivotally connected to the plate 14 adjacent the forward end by means of pivot in the form of bolts 25 while the sockets 21 are both pivotally and slidably connected to the plates 14 adjacent the inner end by means of bolts 26 passing therethrough and through elongated openings or slots 27 in the plates 14. Such bolts 26, mount rollers 28, which are each disposed directly in the slot 27 in order to reduce friction, and washers 29b are strung on the bolts 26 on opposite sides of the rollers 28 to form flanges therefor and they engage the opposite surfaces of the plates 14 to more efficiently mount and guide the operating section 19.

A blade 29 by means of a portion 29a is fastened in any suitable manner in the socket 20 while a handle 30 is fastened at a portion 30a in any suitable manner in socket 21.

As a result of the construction described, the oarsman while seated and facing the bow of the boat will operate the handles 30, in properly moving the blades 29, since the oar sections will pivot and break at the joints 24, the oars and plate 14 as a whole will pivot on the horizontal axis 17, and the operating sections 19 will both pivot and slide at the connections of the bolts 26 and slots 27.

Various changes may be resorted to provided they fall within the spirit and scope of the invention.

I claim as my invention:

An oarlock structure of the class described comprising a plate, mounting means for attachment to a boat, said plate and mounting means having barrels rigid thereon, said barrels being pivotally connected at one edge of the mounting means on an axis transverse with respect to the plate, a hollow cylindrical socket for an oarblade section, a bolt pivoting said section to the plate on one side of said means, a hollow cylindrical socket for an oar handle section, a bolt pivoting the latter section to the plate on the other side of said means, the plate having an elongated slot through which one of the bolts passes to enable shifting movement of one of the sockets, said bolts extending across the interior of the sockets in positions to prevent undue extension of the oarblade section and handle section into the respective sockets, a roller operable in the elongated

slot mounted by the adjacent bolt, said roller having flanges overlapping the upper and lower surfaces of the plate, one end of one of the sockets being reduced, the end of the other socket being solid and extending into the reduced portion, and means pivotally connecting the sockets at said reduced portion and solid portion.

ELWIN R. KOSEY.
